TERMINAL HOOK

Filed April 21, 1930

UNITED STATES PATENT OFFICE

HENRY C. HIERONYMUS, OF NOKOMIS, ILLINOIS

TERMINAL HOOK

Application filed April 21, 1930. Serial No. 446,018.

This invention relates to means for establishing electrical connection between cable power lines or mine track rails and the like and a conductor leading to or from apparatus 5 in which current is utilized. The present invention deals particularly with a novel type of connector which forms the terminal of a conductive wire or cable.

Objects of the invention are: to provide an 10 improved terminal connector having spring pressed means for effecting a clamping positive contact of the connector with an electro-conductive member to which attachment is desired; to provide a device of this character 15 having means for selectively rendering the same adaptable for connection with power cables or conductor rails and the like; and to provide a terminal connector having 20 automatic clamping engagement with an element to which the device is attached in service.

With these and such other objects in view as will be apparent from the description the invention resides in the novel combination, 25 construction and arrangement of parts hereafter described and claimed and illustrated in the accompanying drawings. In the drawings

Figure 1 is an elevation of a connector 30 made up in accordance with the invention and as applied in service position to a power cable or the like.

Figure 2 is substantially a longitudinal section through the connector as shown in Figure 1 but illustrating its service application in connection with a railroad rail.

Figure 3 is a fragmentary elevation of the associated clamping elements of the connector.

Figure 4 is a section taken on the line 4—4 of Figure 2.

In detail the invention comprises a fixed jaw 10 provided at one end with a reversely inclined hook 11 disposed in angled relation 45 to a flat face portion 12 with which the fixed jaw is provided. This jaw 10 is formed upon and integral with the end of a solid cylindrical shank 13 which is externally threaded inwardly from its end to receive 50 thereover a sleeve 14, which sleeve has a

section 15 intermediate its ends internally threaded for attaching engagement over the threaded end portion of the shank 13.

At one end the sleeve 14 is formed with an annular lateral shoulder 16 which forms a 55 retaining flange for a hand grip member 17 made of insulating material and which is disposed over the entire external portion of the sleeve 14, preferably having a threaded engagement therewith at a threaded portion 18 formed externally on the sleeve at the end opposite the retaining flange or shoulder 16.

Extending inwardly from the shoulder 16, the sleeve 14 is formed with a socket as at 19 which surrounds the shank 13 sufficiently to receive therein a coiled expansion spring 20, one end of which abuts against the bottom 21 of the socket 19 and the other end of which abuts against a sliding jaw member 22 slidably and rotatably mounted over the 70 shank 13.

The sliding jaw member 22 is formed substantially as a sleeve over which is externally threaded an insulating body 23 and the jaw member is further formed with an integral 75 forwardly and outwardly inclined lip 24 for a purpose to be described.

The fixed jaw 10 adjacent the commencement of the shank portion 13, is formed with an inwardly directed recess or socket 25 on 80 the side thereof opposite that occupied by the flat face area 12. For strengthening purposes the fixed jaw 10 and wedge hook 11 are provided with a continuous external reinforcing rib 26. The other end of the sleeve 14 is formed with a cylindrical socket 27 which provides clearance for the reception of a conductor terminal member 28 having an internally threaded end portion 29 adapted for screw threaded engagement and connection with the adjacent end of the shank 13 which projects through the sleeve 14 into the cylindrical socket 27, as best illustrated in Figure 2.

With the elements of the device assembled 85 as shown in Figure 2 the connector may be attached to the base flange of a rail 30 as is customary in mining tunnels and the like wherein the track rails are employed as the negative side of a power distribution sys- 100

tem. In such application, the insulated handle 17 is grasped in the hand of an operator and in the other hand the insulated cover 23 of the movable jaw is held and moved inwardly against the action of the spring 20 so that the fixed jaw may be inserted beneath the base flange of the rail and hooked thereover in the manner as shown. The movable jaw 22 is then released and the action of the spring 20 forces the jaw into clamping engagement with the base flange of the rail, bringing the lip 24 into wedging engagement therewith, thus assuring an efficient and positive electrical contact with the rail.

When it is desired to use the connector for establishing contact with a power cable or the like, the movable jaw member 22 is rotated over the shank 13 to dispose the lip 24 forwardly and over the recess or socket 25 formed in the fixed jaw body, the association of parts in this respect being fully illustrated in Figure 3. The body of the fixed jaw 10 is enlarged with respect to the shank 13 so that the shoulder 31 is thus formed behind the recess 25, which shoulder serves as a stop to limit movement of the slidable jaw 22 under action of its spring 20. In this arrangement of the parts, shown in Figure 1, the power cable 32 is securely clamped between the walls of the recess 25 and the inclined wedge face of the lip 24 formed as a part of the sliding jaw member 22. With the exception of the insulator coverings 17 and 23, all parts of the device are made up preferably of brass. The spring 20 is made of suitably tempered steel. Although certain details and materials have been specifically described as entering into the construction and operation of the invention, I desire it to be understood that the same do not constitute limitations but that any desired changes and modifications may be employed in the structural details as will fall within the scope of the invention as claimed.

I claim:

1. A terminal hook comprising a fixed jaw member, a hook on said member, a recessed portion formed in said member, a shank extending integrally from said member, a handle secured to said shank, a movable jaw element slidable on said shank between said handle and fixed jaw and rotatable on the shank, spring means between said handle and movable jaw for urging said movable jaw toward said fixed jaw, a contact lip projecting from one face of said movable jaw, and means on said fixed jaw member for limiting movement of said movable jaw under action of said spring means.
2. A terminal hook comprising a fixed jaw member having opposite faces provided with conductor engageable means, a shank extending therefrom, a movable jaw member slidably and rotatably mounted on said shank, expanding spring means on said shank be-

hind said movable jaw member, and a forwardly and outwardly inclined clamping element on said movable jaw member, said clamping element being selectively disposed with respect to the conductor engageable means on said fixed jaw member by rotation of said movable jaw member to clampingly engage a conductor in either conductor engaging means.

In testimony whereof I affix my signature.

HENRY C. HIERONYMUS.
